UNITED STATES PATENT OFFICE.

SAMUEL S. STOLP, OF MANSFIELD, OHIO, ASSIGNOR TO THE OHIO BRASS COMPANY, OF MANSFIELD, OHIO, A CORPORATION OF NEW JERSEY.

ELECTRICALLY-OPERATED TRACK SWITCH.

Application filed December 15, 1923. Serial No. 680,967.

To all whom it may concern:

Be it known that I, SAMUEL S. STOLP, a citizen of the United States of America, residing at Mansfield, in the county of Rich-
5 land and State of Ohio, have invented cer-
tain new and useful Improvements in an
Electrically-Operated Track Switch, of
which the following is a specification.

My invention relates to electrically oper-
10 ated track switches operated automatically
from the car.

One object of my invention is to produce
a system which works "power on" or "power
off" the system as hereinafter described.

15 Another object of my invention is to pro-
vide a system which will maintain current
to the track switch operating mechanism
for a predetermined time.

Another object of my invention is to pro-
20 vide a system in which independent cooper-
ating means is employed in controlling the
direction of operation of the track switch.

Another object of my invention is to pro-
25 vide a system in which a second operation
of the track switch is prevented while a car
is in operative relation with the system.

My invention resides in the new and novel
construction, combination and arrangement
30 of the various parts and circuits hereinafter
described and set forth in the accompanying
drawings.

In the drawings accompanying my speci-
fication:

Fig. 1 is a schematic drawing showing the
35 general arrangement of circuits usually
found in an electrically operated car and
which are taken account of in the operation
of my invention.

Fig. 2 is a schematic drawing showing the
40 arrangement of the parts and circuits
when the system is in a normal condition.
Under such circumstances, however, the
switch tongue may be in either of its opera-
ble positions.

Fig. 3 is a schematic drawing showing the
45 arrangement of the various parts and cir-
cuits at the instant the system has been set
in operation by the car, operating "power
off".

Fig. 4 is a schematic drawing showing the 50
arrangement of the various parts and cir-
cuits after the car has cooperated with the
system for a predetermined length of time
with "power off".

Fig. 5 is a schematic drawing showing the 55
arrangement of the various parts and cir-
cuits of my invention the instant the system
has been set in operation by the car operating
"power on" and for a predetermined 60
length of time thereafter.

My invention is intended primarily for
use with those cars which are operated by
means of an overhead trolley wheel or cur-
rent collector W mounted on the car by
means of a trolley pole T although it may 65
be operated by cars in which current is sup-
plied thereto by other methods. Most cars
are equipped with heaters H, lights L and
an air compressor F which are connected be-
tween the trolley pole and the ground. The 70
cars are also equipped with motors M and a
controller C therefor, which is under the
control of the car operator. When the con-
troller is closed current will flow through
the motors M and this position I term 75

"power on" and when the controller is open
no current will flow through the motors and
this position I term "power off". The con-
troller C does not in any way control the
current flowing through the apparatus H, L 80

and F and which might be termed the aux-
iliary car current. The current flowing
through the motors flows to ground G. I
have arranged the system herein described
so that the track switch will be operated 85

to the "straight ahead" position when the
collector W engages the system with "power
off" and the track switch will be thrown to
the "curve position" when the collector en-
gages the system with "power on". This op- 90
eration of the track switch, however, may be
reversed by merely reversing the connection
to the track switch operating mechanism,
which change is one which would be evident
to those skilled in the art.

In the system shown in Fig. 2, the numeral
1 represents a trolley wire or conductor. Po-
sitioned adjacent to the trolley conductor is

a pan P provided with two contact members 2 and 3 which are usually parallel and normally insulated from each other. The member 2 is electrically connected to the trolley conductor at all times, but the member 3 is normally insulated therefrom but is electrically connected thereto when the collector W engages the pan P. The contact members 2 and 3 are so related to the trolley conductor 10 that when the collector engages the contact members it will be out of engagement with the trolley conductor and remain so until it is about to pass out of engagement with the pan. Such arrangement of the contact members and conductor is well known to those skilled in the art.

I also employ an electrically operated track switch S provided with two solenoids 4 and 5 each having a connection to the ground through the common conductor 6. The solenoids are provided with a reciprocating core 7 which is drawn inwardly when the solenoid is energized and is drawn outwardly when the solenoid 5 is energized. 25 The core 7 is connected to the switch tongue 8 by means of the rod 9. I also employ an electrically operated and normally open switch A provided with operating coils 10 and 11 and a switch arm 12, the coils being 30 connected to oppose each other when energized as indicated by the arrows thereon. The coils 10 and 11 are mounted on a magnetic core, which is also true of the other switch coil later referred to although a 35 moving plunger may be substituted for the magnetic core, as is well known in the art. One terminal of each coil 10 and 11 is connected to the contact member 2 by the common conductor 38, while the remaining terminals of the coils 10 and 11 are connected to the trolley conductor 1. The other connection for the coil 10 is the conductor 13 which runs directly to the trolley conductor and the other connection for the coil 11 40 is the conductor 14, contact 15, switch arm 16 and conductors 17 and 18. The circuit composed of these last elements is connected to the trolley conductor and normally open at the contact 15. The coil 10 is so proportioned that when the current collector engages the pan P with "power off" such current as may flow through the coil A to the pan and thence through the auxiliary car circuits will not produce sufficient ampere turns to move the arm 12, but if the 45 engagement is made with "power on" a heavy flow of current will pass through the motors M which will primarily pass through the coil 10 and this will produce sufficient ampere turns to pick up the arm 12.

It will be noted that the coil 11 cannot be energized until the switch arm 16 engages the contact 15 as later described. Cooperating with the arm 12 is a contact member 19 50 connected to the solenoid 5 by the conduct-

tor 20. It will be noted that when the arm 12 engages the contact 19 that current can then flow through the solenoid 5 as the switch arm 12 is connected to the trolley conductor 1 through the conductors 17, 21 70 and 22. I also employ a switch B which is provided with two coils 23 and 24 of equal energizing value, but connected for differential operation as indicated by the arrow thereon. One terminal of each coil 23 and 75 24 is connected to the conductor 20 by means of the conductor 25 thereby providing a ground connection for these coils by way of the solenoid 5. The remaining terminal of the coil 23 is connected to a contact 80 member 26 by means of the conductor 27 and the remaining terminal of the coil 24 is connected to the contact member 3 by means of the conductors 28 and 29. The switch B is also provided with a switch arm 30 which 85 is normally open, but when closed engages the contact 31 which is connected to the solenoid 4 by the conductor 32. The switch arm 30 is also connected to the trolley conductor 1 by means of the conductors 17, 21 90 and 33.

I also employ a switch C which is provided with a coil 34 having one connection 35 to the ground and another connection 36 which leads to the contact member 3 by way 95 of the conductor 28. I prefer to so construct the switches A, B and C that they will be slow in release operation and I prefer to so construct the switch A that with "power on" application this switch will close before 100 the others and B will close before C.

If the collector W engages the pan P with "power off" the contact members 2 and 3 will be electrically connected and of the same potential as the trolley wire as the contact member 2 is electrically connected to the trolley conductor by way of the elements 38, 10 and 13. As soon as the member 3 is electrically connected to the trolley conductor current will flow through the coil 34 to ground thereby energizing the same and closing the switch arm upon its contacts. The switch A, however, will not be affected with a "power off" application. As soon as the contact member 3 is energized with "power off" application the switch B will also be placed in operation in that the coil 24 will be energized since it is connected to the contact member 3 and also has a ground provided by way of the solenoid 5. As soon 110 as the solenoid 24 is energized it will close the switch arm 30 with its contact 31 and current is then free to flow from the trolley conductor 1 to the solenoid 4 by way of the switch B.

As soon as the switch C closes the coil 23 will be energized and will act in opposition to the coil 24 and after a lapse of time the arm 30 will drop. It is the intention, however, that the time lag shall be sufficient to 120 125

provide ample time for the energization of the solenoid 4. It is evident that the switch B will remain open as long as the switch C remains closed and that the switch C will remain closed as long as the contactor engages the pan P so that if the car should come to rest either "power on" or "power off" with the collector in engagement with the pan P, the switch C will remain closed, but the switch B will open after a predetermined time and will remain open thereby preventing the burning out of the solenoid 4.

As soon as the switch C closes the coil 11 will be energized, but such energization to the extent of affecting the arm 12 will not take place unless the collector is in engagement with the pan P with "power on," therefore, if the collector initially engages the pan P with "power off" and comes to rest in engagement with the pan P and when the operator throws his controller to "power on" to move his car, there will be provided two paths for the current, namely, through the coils 10 and 11 in place of one path only through the coil 10, and this division of current will be in proportion to the resistance of the two circuits and is so proportioned as to permit enough current to flow through either coil to effect the arm 12.

50 If the current collector initially engages the pan with "power on" the coil 10 will be instantly energized and pick up the arm 12 into engagement with the contact 19 and this pick up, as already stated, is preferred to be in advance of the closing of the switch C in view of the parallel circuit provided through the coil 11. After the switch A has closed if the division of current through the coils 10 and 11 is equal the arm 12 will drop 55 after a lapse of time as the coils oppose each other. As soon as the switch A closes, current flows from the trolley conductor, through the solenoid 5, energizing the same and moving the switch tongue to the "curve" position if it should be in the "straight ahead" position. If, however, the division of current through the coils 10 and 11 is made unequal by properly proportioning the ampere turns so that one coil, preferably 10, 60 will have more energizing value than the other, then the coil 10 will have a holding value equal to the difference in the ampere turns between the coils and the arm 12 will be closed so long as the collector engages the pan with "power on." This time application of the current to solenoid 5, however, will not be sufficient to cause the solenoid to burn out. As soon as the switch A closes and which, as already stated, is preferred to be in advance of the closing of the switch B, the switch B cannot close for then the conductor 20 will be directly connected to the trolley conductor 1 and there will be no difference of potential across the terminals of the coils 23 or 24, therefore there will be no

flow of current therethrough and the switch B will not close.

To sum up the operation of the system, if the operator desires to go "straight ahead" he sets his controller to "power off" with the intention of coasting past the pan P. As soon as the collector engages the pan P the switch C will be closed, likewise current will flow through the coil 24 of the switch B, closing the same, all as shown in Fig. 3, and as soon as the switch C is closed the coil 23 will be energized thereby placing the coils 23 and 24 in differential operation and after a lapse of time the arm 30 will drop, but in the interval, current will be flowing through the switch B to the solenoid 4 thereby placing the track switch in the "straight ahead" position, all as shown in Fig. 4. Fig. 3 shows the parts at the instant the collector has engaged the pan P with "power off" and Fig. 4 shows the condition of the parts after the collector has engaged the pan for a predetermined time. If for any reason the car comes to rest after the said predetermined time with the collector in engagement with the pan, the relation of the parts will be as shown in Fig. 4, while such engagement takes place. When the car has passed beyond the pan the system will return to normal as shown in Fig. 2. When the car starts up from rest on the pan, the switch A will not be affected because the heavy current which flows through the motors is divided between the coils 10 and 11 since the switch C is closed, and will not produce sufficient ampere turns in either coil 10 or 11 to effect the arm 12 since the coils are connected to function in opposition.

All of the switches are provided with retarded release factors and this retardation may be brought about by various well known constructive principles in regard to such devices as a copper or brass sleeve about the core or coil of the magnet, as indicated by 37, or it may be brought about by the spacing of the switch arms with respect to their cores when in a closed position, or a combination of these or by a dash-pot arrangement, etc., or the switches A and B may depend upon the differential action of their coils.

If the operator desires to take the "curve" he will turn his controller to "power on" with the intention of coasting over the pan P. When the collector engages the pan P with "power on," the coil 10 will be energized and the switch A closed and also the switch C will immediately close following the closing of the switch A. As soon as the switch C closes the current will flow through the solenoid 5 and the core 7 will be drawn out and the tongue moved to the "curve" position as shown in Fig. 5. It is very unusual for a car to come to rest with its collector in engagement with the pan if it starts

across the pan with "power on," but if the coils 10 and 11 are of equal ampere turns the switch will open automatically after a lapse of time.

6. There are, of course, modifications and rearrangements of the parts which can be made from those shown in the above disclosure and which will still fall within the scope of my invention.

7. I claim:

1. A switch operating system comprising an electrically operated track switch, a trolley conductor, a contact pan to be engaged by a current collector, a branched circuit for conducting current to the track switch to operate the switch in the direction desired when the collector engages the pan with "power on" or "power off", a control switch to control the branched circuit and having two operating coils, one coil to position the control switch to operate the track switch when the system is operating "power on" and another coil opposing the first coil to prevent the control switch operating after an initial operation of "power off".

2. A switch operating system comprising in combination, an electrically operated track switch, a contact pan to be engaged by a current collector, a normally open branched circuit to conduct current to the track switch to operate the track switch in the desired direction, a control switch to control the closing and opening of one of the branch circuits and provided with a closing coil operable when the system is working "power on" and a coil preventing the closing of the control switch if the system is initially working "power off".

3. A switch operating system comprising in combination, an electrically operated track switch, a pan to be engaged by a current collector, a circuit to conduct current to the track switch, a control switch to control the circuit and having two operating coils, one arranged to be placed in series with the car motors when the collector engages the pan with "power on" and the other to be placed in series with the car motors after the collector engages the pan and opposing the action of the first coil to prevent a second operation of the track switch after the collector engages the pan with "power off".

4. A switch operating system comprising in combination, an electrically operated track switch, a pan to be engaged by a current collector, a circuit to conduct current to the track switch, a control switch to control the circuit and having two operating coils, one arranged to be placed in series with the car motors when the collector engages the pan with "power on" and the other to be placed in shunt with the first coil after the collector engages the pan and opposing the action of the first coil to prevent a sec-

ond operation of the track switch after the 65 collector engages the pan with "power off".

5. In a switch operating system the combination of, a trolley conductor, an electrically operated track switch, a pan to be engaged by a current collector, a branched 70 circuit leading to the track switch to operate the same in the direction desired, a control switch to control each branch circuit, one switch provided with operating coils connected between the conductor and the 75 ground and having the car motors in series with said coils when the system is working "power on" and the other switch provided with operating coils connected between the conductor and the ground and having the 80 track switch operating means in series with said coils.

6. In a switch operating system the combination of, a trolley conductor, an electrically operated track switch, a pan to be engaged by a current collector, a branched circuit leading to the track switch to operate the same in the direction desired, a control switch to control each branch circuit, one switch provided with opposing operating 85 coils connected between the conductor and the ground and having the car motors in series with said coils when the system is working "power on" and the other switch provided with opposing operating coils connected between the conductor and the 90 ground and having the track switch operating means in series with said coils when the system is working "power off".

7. In a switch operating system the combination of, an electrically operated track switch, a trolley conductor, a pan to be engaged by a current collector, a circuit to energize the track switch, a control switch for said circuit, an operating coil for the control 105 switch connected between the conductor and the pan, a second coil for said control switch connected between the conductor and the pan and an electrically controlled switch for controlling the second coil. 110

8. In a switch operating system the combination of, an electrically operated track switch, a trolley conductor, a pan to be engaged by a current collector, a circuit to energize the track switch, a control switch for said circuit, an operating coil for the control switch connected between the conductor and the pan, a second coil for said control switch connected between the conductor and the pan and an electrically controlled switch to 115 complete the circuit of the last said coil after the collector engages the pan.

9. In a switch operating system the combination of, a trolley conductor, an electrically operated track switch, a pan to be engaged by a current collector, a branched circuit leading to the track switch to operate the same in the direction desired, a con- 125

trol switch to control each branch circuit, one switch provided with operating coils connected between the conductor and the ground and having the car motors in series with said coils when the collector engages the pan with the system working "power on" and the other switch provided with operating coils connected between the conductor and the ground when the collector 10 engages the pan.

10. In a switch operating system the combination of, an electrically operated track switch, a trolley conductor, a pan to be engaged by a current collector, a normally open circuit to energize the track switch, a control switch to close said circuit, an operating coil for the control switch connected between the conductor and the pan, a second coil for said control switch connected between the conductor and the pan and an electrically controlled switch for controlling the second coil.

11. In a switch operating system the combination of, an electrically operated track switch, a trolley conductor, a pan to be engaged by a current collector, a normally open circuit to energize the track switch, a control switch to close said circuit, an operating coil for the control switch connected between the conductor and the pan, a second coil for said control switch acting in opposition to said first coil and connected between the conductor and the pan and an electrically controlled switch for controlling the second coil.

12. In a switch operating system the combination of, an electrically operated track switch, a trolley conductor, a pan to be engaged by a current collector, a circuit to energize the track switch, a control switch for said circuit, an operating coil for the control switch connected between the conductor and the pan, a second coil for said control switch connected between the conductor and the pan, a control switch for controlling the second coil, and a coil for operating the last said switch and deriving its current from the pan.

13. In a switch operating system the combination of, an electrically operated track switch, a trolley conductor, a pan to be engaged by a current collector, a circuit to energize the track switch, a control switch for said circuit, an operating coil for the control switch operating with "power on" the system, a second operating coil for said control switch to oppose the action of the first coil to prevent a second operation of the track switch, and an electrically operated switch to control the energization of the second coil after the collector has engaged the pan.

14. A switch operating system comprising in combination, an electrically operated

track switch, electrical circuits leading to the track switch, a switch controlling one of the circuits and provided with a coil to close the switch and circuit with "power on" the system and a coil to oppose the action of the first coil when the system is working "power off," a switch controlling another of the circuits and provided with a coil to close the switch and circuit when the system is working "power off" and a coil to oppose the action of the said coil after a predetermined time to open said switch.

15. A switch operating system adapted to work "power on" or "power off" the system comprising in combination, a branched operating circuit to operate the track switch to either of its operable positions, a control switch to close the "power on" branch circuit and a coil to operate the switch when the system is working "power on," and a coil to act in differential to the first coil to prevent the control switch closing when the system is working "power off."

16. A switch operating system comprising in combination, an electrically operated track switch, a pan to be engaged by a current collector, a circuit to conduct current to the track switch, a control switch to control the circuit and having two operating coils, one arranged to be placed in series with the car motors when the collector engages the pan with "power on" and the other connected to counteract the energizing effect of the first coil after the collector engages the pan with "power off."

17. A switch operating system comprising in combination, an electrically operated track switch, a pan to be engaged by a current collector, a circuit to conduct current to the track switch, a control switch to control the circuit and having two operating coils, one arranged to be placed in series with the car motors when the collector engages the pan with "power on" and the other connected to counteract the energizing effect of the first coil after the collector engages the pan with "power off" and means to control the energizing of the second coil.

18. In a switch operating system the combination of, an electrically operated track switch, electric circuits leading to the track switch to operate the same in the direction desired, a switch to control one circuit when the system works "power off", operating means therefor, another switch to control the other circuit and to prevent the operation of the first switch when the system works "power on" and provided with means to prevent a second operation of the track switch when the system initially works "power off".

19. In a switch operating system the combination of, an electrically operated track switch, electric circuits leading to the track

switch to operate the same in the direction desired, a switch to control one circuit when the system works "power off", operating means therefor, another switch to control the other circuit and to prevent the operation of the first switch when the system works "power on".

20. In a switch operating system the combination of, an electrically operated track switch, electric circuits leading to the track switch to operate the same in the direction desired, a switch to control one circuit when the system works "power off", operating means therefor, another switch to control the other circuit and a switch to control simultaneously the operation of both the above control switches to open one switch and prevent the closing of the other switch.

21. In a switch operating system the combination of, an electrically operated track switch, electric circuits leading to the track switch to operate the same in the direction desired, a switch to control one circuit when the system works "power off", operating means therefor, another switch to control the other circuit and to prevent the operation of the first switch when the system works "power on" and provided with means to prevent a second operation of the track switch when the system initially works "power off", and to maintain said control switch closed while the system is operating with "power on".

22. A switch operating system comprising in combination, an electrically operated track switch, operating circuits leading to the track switch to operate the switch to its operable positions, electrically operated control switches for said circuits to control the direction of movement of the track switch, and an electrically operated switch to control the operation of the above control switches and operated by the current collector in a moving car to prevent the closing of either switch after a predetermined length of time.

23. A switch operating system comprising in combination, an electrically operated track switch, operating circuits leading to the track switch to operate the switch to its operable positions, electrically operated control switches for said circuits to control the direction of movement of the track switch, and an electrically operated switch to control the operation of the above control switches to prevent one switch closing while the other switch is closed.

24. In a switch operating system the combination of, an electrically operated track switch, circuits leading to the track switch, an electrically operated control switch for each circuit to close each circuit independent of the other circuit and means controlled by one switch when closed to prevent the closing of the other switch by short circuit-

ing the operating means of the said other switch.

25. In a switch operating system the combination of, an electrically operated track switch, circuits leading to the track switch, a control switch for each circuit, means to prevent the closing of one switch when the other switch is closed by short circuiting the operating means of said other switch and means to prevent the closing of the first switch while the second switch is closed, all to operate the track switch to the desired position and to prevent a second operation of the track switch.

26. In a switch operating system the combination of, an electrically operated track switch, circuits leading to the track switch for separate operation, a control switch in each circuit to close the circuit depending whether the system works "power on" or "power off" and to hold the circuit closed for a predetermined time and means to maintain the control switches inoperative after their initial closing and opening to prevent a second operation of the system.

27. A switch operating system comprising, a trolley conductor, a pan to be engaged by a current collector with "power on" or "power off" the motors and having two contact members, a track switch S having electrical operating means to move the switch to the desired position, a normally open switch B to control a circuit leading to the track switch and provided with electrical operating means to close the switch when the collector engages the pan with "power off" and provided with means to open the switch after a predetermined time, a normally open switch A to control a circuit leading to the track switch and provided with electrical operating means to close the switch when the collector engages the pan with "power on" and provided with means to prevent the closing of the switch while the switch B is closed the said switch also operating to prevent the closing of the switch B when the collector engages the pan initially with "power on," an electrically operated switch to close circuits controlling the opening means for the switch B and the means preventing the closing of switch A after the collector engages the pan and circuits connecting the above parts for operation of the system as described.

28. In a switch operating system the combination of, an electrically operated track switch provided with circuits leading thereto to operate the switch in either of its operable positions, the circuits separately energized, depending upon a moving car operating with "power on" or "power off" the motors, and a control switch in the circuit controlled by "power on" the motors to close the same, means to operate the switch to closed position and means to open the switch

after a predetermined time of application of current with "power on" the motors.

29. In a switch operating system working with "power on" or "power off" the 5 motors, the combination of, an electrically operated track switch, a pan to be engaged by a current collector, circuits leading to the track switch, a control switch operating with "power on" the motors to close one of 10 the circuits, electrically operated means to

close the switch with "power on," means to prevent the operation of the control switch to close the said circuit when the other circuit is closed by depriving the operating means of sufficient current to operate it and 15 simultaneously neutralize wholly or partially the effect of the remaining current therein.

In testimony whereof I affix my signature.

SAMUEL S. STOLP.
